ATTORNEY

UNITED STATES PATENT OFFICE.

HERMAN LEVY, OF NEW YORK, N. Y.

DESIGN FOR THE ORNAMENTATION OF PILE FABRICS.

SPECIFICATION forming part of Design No. 18,906, dated June 17, 1890.

Application filed April 25, 1890 Serial No. 349,506. Term of patent 3½ years.

To all whom it may concern:

Be it known that I, HERMAN LEVY, a subject of the Emperor of Germany, residing at New York city, in the county of New York and State of New York, have produced and invented a new and original Design for Pile Fabrics, of which the following is a specification, reference being had to the accompanying drawing, forming part thereof.

10 The figure is a face view of the cloth.

My invention consists in the design for the ornamentation of all fabrics which come within the class known as "pile fabrics."

15 In the drawing, A is the ground of the design, and B the ornamentation. This orna-

mentation appears, as in the drawing, in the shape of a fanciful Y, having various curved branches and leaf-like portions C extending radially therefrom.

This design for the ornamentation of pile 20 fabrics produces an elegant and distinguished effect to the eye, and stands out and is broadly contrasted with the ground.

I claim—

The design for the ornamentation of pile 25 fabrics herein shown and described.

HERMAN LEVY.
